(57) **CLAIM**

The ornamental design for a neon sign, as shown and described.

DESCRIPTION

FIG. 1 is a front top perspective view of the first embodiment of a neon sign, showing my new design;

FIG. 2 is a back bottom perspective view thereof;

FIG. 3 is a front view thereof;

FIG. 4 is a back view thereof;

FIG. 5 is a left side view thereof;

FIG. 6 is a right side view thereof;

FIG. 7 is a top view thereof;

FIG. 8 is a bottom view thereof;

FIG. 9 is a front top perspective view of the second embodiment of a neon sign;

FIG. 10 is a back bottom perspective view thereof;

FIG. 11 is a front top perspective view of the third embodiment of a neon sign; and,

FIG. 12 is a back bottom perspective view thereof.

The broken lines shown in the drawings depict portions of the neon sign that form no part of the claimed design.
